United States Patent Office.

WILLIAM H. GIBBS, OF CINCINNATI, OHIO

Letters Patent No. 92,601, dated July 13, 1869.

IMPROVEMENT IN BOTTLE-STOPPERS.

The Schedule referred to in these Letters Patent and making part of the same.

To whom it may concern:

Be it known that I, WILLIAM H. GIBBS, of Cincinnati, Hamilton county, Ohio, have invented a new and useful Bottle-Stopper for mineral-water bottles, &c.; and I hereby declare the following to be a full, clear, and exact description thereof, reference being had to the accompanying drawings, making part of this specification.

My invention relates to a bottle-stopper, more especially intended for mineral-water bottles; and consists in a rigid, but movable frame, having a peripherally grooved head, carrying a ring of India rubber, which acts as a stopper to the bottle when the frame is held down by means hereafter described.

Figure 1 is a perspective view of the bottle-stopper in position in the bottle.

Figure 2 is a perspective view, showing the stopper removed from the bottle.

Figure 3 is a vertical section in its closed condition.

Figure 4 is a horizontal section at the line *x-x*.

A is a ring, of India rubber, having preferably a D-shaped transverse section, the straight side being upon the outside for contact with the neck of the bottle. This rubber ring rests in a groove surrounding the head B of a frame, whose side-bars C, after extending outward from the head, extend downward below the bulge *e*, at the top of the neck *E* of the bottle.

At the lower ends of the side-bars C, are perforations *f*, which receive a wire ring, F, made to slide upon the neck of the bottle below the bulge.

Surrounding the neck, immediately beneath the bulge *e*, is a metallic ring, having horizontal or slightly inclined wings G, and thumb-pieces H. These wings, by the partial revolution of the ring, are made to engage in notches *c*, upon the inner sides of the bars C. That portion of the ring embracing the wings G and thumb-pieces H, with the connection between the two wings, is shown as cast in one piece, which, after application to the neck of the bottle, is held thereon by a wire tie, I, which is passed around the necks of the thumb-pieces.

The operation is as follows:

The bottle being filled, and the stopper forced downward in the usual manner, the wings G are engaged with the notches *c*, which prevents the raising of the stopper when removed from the depresser.

It will be seen that the side-bars C are slightly curved sideways at their lower ends, to allow the stopper to be thrown over on that side for the free injection or exit of the liquid.

I claim herein as new, and of my invention—

The combination and arrangement of the rubber A, or its equivalent, frame B C *c*, wire F, and holding-ring G H, substantially as described.

In testimony of which invention, I hereunto set my hand.

W. H. GIBBS.
